UNITED STATES PATENT OFFICE

GEORGE DOUGLAS WIEPERT, OF NEW HAVEN, CONNECTICUT, ASSIGNOR TO SARGENT & COMPANY, OF NEW HAVEN, CONNECTICUT, A CORPORATION OF CONNECTICUT

DESIGN FOR A SHELF OR THE LIKE

Application filed August 25, 1932. Serial No. 44,689. Term of patent 14 years.

To all whom it may concern:

Be it known that I, GEORGE DOUGLAS WIEPERT, a citizen of the United States, residing in New Haven, in the county of New Haven and State of Connecticut, have invented a new, original, and ornamental Design for Shelves or the like, of which the following is a specification when taken in connection with the accompanying drawing.

Fig. 1 is a perspective view of a shelf, embodying my invention; and

Fig. 2 is a sectional view on line 2—2 of Fig. 1.

I claim:

The ornamental design for a shelf or the like substantially as shown.

GEORGE DOUGLAS WIEPERT.
